DUFFEL BAG

Filed Aug. 29, 1940

Fig. 1.

UNITED STATES PATENT OFFICE

2,254,578

DUFFEL BAG

Frank J. O'Brien, Pelham, N. Y.

Application August 29, 1940, Serial No. 354,754

2 Claims. (Cl. 190—43)

The invention relates generally to luggage or baggage equipment and primarily seeks to provide a novel form of duffel bag which can readily be collapsed to a flat condition to permit folding or rolling and out-of-the-way storage, or placement in another container or piece of luggage, and which can readily be set up into condition for carrying clothing, sports equipment or other materials customarily placed in such knockabout luggage.

An object of the invention is to provide a bag of the character stated which is formed of flexible blank material formed so that it can lie flat, and which includes end and body portions including edges which can be brought together to form base, side, end and top portions, and "zipper" means for securing said edges in bag forming relation and releasable for allowing a collapsing of the bag portions to the flat blank condition.

Another object of the invention is to provide a collapsible duffel bag of the character stated in which the "zipper" means are so arranged that a single lock can be used to lock the bag.

Another object of the invention is to provide a collapsible duffel bag of the character stated in which the "zipper" means effective to join the side and end edges at each end of the bag are mounted inside and accessible only inside the bag, and the "zipper" means effective to join the side portion edges along the top are mounted outside the bag, thereby to enable locking of the bag by a single lock effective to secure said single outside "zipper" means.

With the above and other objects in view that will hereinafter appear, the nature of the invention will be more clearly understood by following the detailed description, the appended claims, and the several views illustrated in the accompanying drawing.

In the drawing:

Figure 1 is a perspective view illustrating the invention.

Figure 2 is a plan view illustrating the bag in the collapsed or flattened out condition.

Figure 3 is an enlarged detail plan view illustrating the end extremity of the bag at which the lock is positioned when in locked condition.

Figure 4 is a fragmentary perspective view of the other end of the bag and illustrates a partially separated condition of the meeting edges of the bag.

In the example of embodiment of the invention herein disclosed, the blank from which the collapsible bag is made up is shaped to comprise a

rectangular base or bottom portion 5, an integral side extension 6 projecting from one major length edge thereof, and an integral side extension 7 projecting from the other major length edge thereof. Ends respectively designated 8 and 9 also project integrally from the minor length edge portions of the rectangular base or body 5, and these each include inwardly and upwardly converging upper edge portions 10 which merge into a short top or terminal portion 11 disposed parallel to the bottom or base when the bag is set up in the manner illustrated in Figure 1 of the drawing.

When the bag is being set up as illustrated in Figure 1, the flexible material of which the bag is composed, preferably thin leather, leather substitute, canvas, or the like, is bent up at the major and minor length edge portions of the base, as at 12, to dispose the side portions 5, 6 and the end portions 8, 9 uprightly with respect to the base or bottom 5. In order to cause the sides 6 and 7 to conform to the edge shape of the ends 8 and 9, said sides are bent at 13 to conform to the upwardly and inwardly converging edges 10 of said ends, and as at 14 to conform to the horizontal top or terminal edge portions 11.

While it is preferred that the bag ends be formed in the manner illustrated in Figures 1 and 2 of the drawing, and as hereinbefore described, it is to be understood that the ends may be round or triangular in shape if a generally cylindrical, or a triangularly shaped bag should be desired.

Where the edges of the sides and ends meet at the base, they are extended a short distance into the base in curved relation, as at 15, as is best illustrated in Figure 2 of the drawing. The meeting edges of the side and end portions of the bag define the shape of the bag in combination with the bend lines 12, 13 and 14 hereinbefore described, and these meeting edges have "zipper" strips 16 attached thereto in the manner illustrated in Figures 1 and 2 of the drawing.

The bag-forming and securing "zipper" equipments of which the strips 16 are a part include the usual "zipper" stops 17 at the upper terminals of the side and end meeting edges in the manner best illustrated in Figures 3 and 4, and these "zipper" equipments also include the usual zippers 18 or securing slides, one thereof being provided at each side of each end of the bag. Each such cooperating pair of "zippers" 18 are adapted to seat at the terminal portions of the side and end meeting edges which extend into the base in curved relation at 15 when the bag is in the flattened position illustrated in Figure 2, and to come

together over the end terminal portions 11 when the bag is set up as illustrated in Figure 1 of the drawing.

The "zippers" 18 include the usual pull elements 19 and are disposed inside the bag when it is in the set up position illustrated in Figure 1, thus being inaccessible from outside the bag except through the top opening of the bag provided between the meeting edges of the sides 6 and 7.

The edges of the sides 6 and 7 which meet longitudinally across the top of the bag and through which the interior of the bag is accessible are provided with cooperating "zipper" strips 20 which include the usual stop members 21 at one end and are secured together or separated by manipulation of the usual slidable "zipper" member 22. The zipper equipment for the meeting edges of the sides or the main opening of the bag is of the type which enables complete separation of said opening edges, this being necessary to permit the bag to be entirely collapsed into the flat as illustrated in Figure 2. The "zipper" element 22 includes a pull extension 23, preferably a chain, which may extend over the end of the bag when the "zipper" has been drawn to the position for closing and securing the mouth of the bag formed by the meeting edges of the sides 6 and 7, and this extension may carry a lock 24 at its end which may be applied to a keeper member 25 secured to the end 9, in the manner illustrated in Figure 1, thereby to secure the whole bag against unauthorized entry.

At the end of the bag opposite that at which the "zipper" 22 is positioned in Figure 1, separable elements 26 are fixed to the corners of the sides 8 and 9 in the manner illustrated in Figure 4. When it is desired to separate these ends in order to flatten out the bag, the "zipper" member 22 can ride down onto one of said elements 26 in the manner illustrated in Figure 4, and the insert portion 27 of the other element which is mountable in and withdrawable from the receiving slotway 28 formed in the "zipper" 22 and the slotway extension 29 in the element 26 can be removed from said slotways 28 and 29 in the manner illustrated in said Figure 4.

Any form of separable "zipper" structure can be employed, and the specific structure 22, 26-29 is but an example of such separable equipment. This particular equipment is disclosed in the U. S. Letters Patent issued to M. Kiessling et al. 2,169,608, on August 15, 1939.

When the bag is in the flat condition illustrated in Figure 2 of the drawing it can be rolled up or folded, and placed in a bag, or in a desk, or in any convenient storage place where it will consume a minimum of space.

When it is desired to use the bag, the "zippers" 18 then resting in the curved terminals 15 formed by the inwardly curved meeting edges of the sides and ends 6, 7, 8, 9 in the base or bottom 5 are drawn upwardly along the "zipper" strips 16 at the corners of the bag, thereby drawing the bag, corner by corner, into the condition illustrated in Figure 1. The bag is then filled through the open mouth defined by the meeting edges of the sides 6 and 7, and then the insert portion 27 of the element 26 is inserted into the "zipper" element receiving slotways 28, 29, after which the "zipper" 22 can be drawn along the "zipper" strips 20 to close the bag in the manner illustrated in Figure 1. When the bag mouth is thus closed the "zippers" 18 are inaccessible

because they are within the bag, and if it is desired to lock the bag the lock 24 is applied to the keeper 25 and the single lock 24 will secure the whole bag against unauthorized entry.

It is to be understood that the "zipper" members 18, 19 hereinbefore referred to preferably are of the clamp-locking type well known in the art, that is the type which is automatically clamped against sliding movement whenever the pull elements are laid flat against the "zipper" slide members as shown in dotted lines in Figure 3. This type of "zipper" element is so well known in the art that additional description and illustration thereof is thought to be unnecessary. Obviously, when these "zipper" members are brought to the position illustrated in Figure 3 and there clamped by flat positioning of the pull members 19 from within the bag, sliding movement cannot be imparted to the "zipper" members from without the bag.

While it is preferred that the "zipper" members 18 be placed so that their pull members are accessible within the bag only, so that the whole bag can be secured by a single lock as hereinbefore described, it will be obvious that these "zipper" members can be placed so as to be accessible outside the bag if desired. When these elements are placed so that the pull members are accessible outside the bag, provision can be made for locking the bag with two locks instead of one as previously described. In this adaptation of the invention the chain 23 attached to the "zipper" member 22 can be passed through apertures in the pull members of the "zipper" elements 18 and then lock-secured to the keeper member 25. It is to be understood, of course, that a similar locking chain would be passed through the pull members 19 at the opposite end of the bag.

The term "duffel" bag herein used is not to be considered an intentional limitation as to the form or kind of bag since the invention relates to the specific collapsible nature of the bag and not to any particular form or shape of the bag or the kind of material employed in its manufacture.

It is, of course, to be understood that the details of structure and arrangement of parts may be variously changed and modified without departing from the spirit and scope of my invention provided they come within the scope of the claims.

Having thus described the invention, what I claim as new and desire to secure by Letters-Patent is:

1. A one piece duffel bag of foldable material comprising a bottom portion, side and end members all integral therewith, said end members having the edges thereof extended upwardly from the bottom and converging inwardly toward each other at the upper end, the side members having edges lying in parallel planes and dimensioned so as to extend along the edges of the ends in abutted relation thereto and meet centrally at the top portion of the ends in abutted relation, a plurality of independent "zipper" equipments for joining the adjacent edges of the side members and end members, the manipulating devices for the "zippers" when the side and end members are joined being disposed at the top portion of the side members, said side and end meeting edges being extended into the bottom to enable the side and ends when separated to lie flat relative to the bottom and an independent "zipper" equipment for joining the adjacent edges of the side members, said last named "zipper" equipment being separable throughout the whole length of the

meeting edges whereby the end members and side members may be disconnected from each other and folded for storage.

2. A one piece duffel bag of foldable material comprising a bottom portion, side and end members all integral therewith, said end members having the edges thereof extended upwardly from the bottom and converging inwardly toward each other at the upper end, the side members having edges lying in parallel planes and dimensioned so as to extend along the edges of the ends in abutted relation thereto and meet centrally at the top portion of the ends in abutted relation, a plurality of independent "zipper" equipments for joining the adjacent edges of the side members and end members, the manipulating devices for the "zippers" when the side and end members

are joined being disposed at the top portion of the side members, said side and end meeting edges being extended into the bottom to enable the side and ends when separated to lie flat relative to the bottom and an independent "zipper" equipment for joining the adjacent edges of the side members, said last named "zipper" equipment being separable throughout the whole length of the meeting edges whereby the end members and side members may be disconnected from each other and folded for storage, said manipulating devices for the "zippers" at each corner being disposed on the interior of the duffle bag so as to be concealed within the bag when the meeting edges of the side members are closed by the "zipper" equipment therefor.
